UNITED STATES PATENT OFFICE

PHELPS M. FREER, OF DETROIT, MICHIGAN, ASSIGNOR, BY DIRECT AND MESNE ASSIGNMENTS, OF FIFTY-ONE PER CENT TO CHARLES H. LEWIS, OF CLEVELAND, OHIO, AND FORTY-NINE PER CENT TO DETROIT AND SECURITY TRUST COMPANY, TRUSTEE, A CORPORATION OF MICHIGAN

PISTON

Original application filed January 18, 1928, Serial No. 247,605. Divided and this application filed March 11, 1929. Serial No. 345,955.

This invention relates to improvements in pistons designed particularly for use in internal combustion engines, as described in the present specification and illustrated in the 5 accompanying drawing which forms a part of the same, and is a division of my application for Letters Patent of the United States for improvements in pistons, filed January 18, 1928, and serially numbered 247,605.

10 The objects of the invention are to provide a composite piston comprising a head of light material having high heat conducting qualities, and a skirt of maximum wearing qualities joined to the head by a simple form of 15 spring bracelet which further serves to maintain the head and skirt in true concentric relationship.

In the drawings:

20 Fig. 1 is an elevational view of the piston with a portion of the skirt thereof broken away to better illustrate the construction.

Fig. 2 is a side elevation detail view of the 25 head with one quarter thereof broken away, the head being turned ninety degrees from the view shown in Fig. 1.

Fig. 3 is a side elevation view of the spring bracelet.

30 Fig. 4 is a side elevation of the skirt member with portions thereof broken away to better illustrate the construction.

Fig. 5 is a sectional view taken as on the 35 line 5—5 of Fig. 1 showing the connection between the bracelet and the head member.

Fig. 6 is a fragmentary sectional view taken 40 on the line 6—6 of Fig. 1, illustrating the relationship of certain bracelet fingers with cooperating notches formed in the skirt member.

Like numerals of reference indicate corresponding parts in each figure.

Referring to the drawings, the numeral 10 indicates the piston head, having the usual piston ring grooves 11, and also having the 45 downwardly depending annular portion 12 terminating at or near the piston pin bosses 13, whereby the said bosses are adequately supported from the head.

The portion 12 of the head has an annular groove 14 cut therearound adjacent its lower

end, and extends downwardly from a locking shoulder 15.

The head as described is preferably made of cast aluminum or other light alloy having maximum heat conducting qualities, while 55 the skirt 16 is made of a metal such as a cast nickel iron alloy or the like, which possesses high wearing qualities and a very low coefficient of expansion.

The skirt 16 is made of a plain cylindrical form having a small ledge or inwardly extending flange 17 around the bottom for reinforcing purposes, and likewise an inwardly extending flange 18 around the top, the flange 18 being finished on its under side 19 with 60 a bevel of a definite angle for purposes as hereinafter described.

The head 10 and skirt 16 are cast or otherwise formed and finished as separate pieces 70 and are then joined by a spring bracelet having a split annular inturned lower end 21 and upwardly and outwardly extending fingers 22, 23 and 24, the fingers 22 being slightly longer than the fingers 23, so that the bracelet may be sprung around the lower part 12 75 of the head 10 similar to a piston ring, with the lower inturned portion 20 fitting snugly in the groove 14 in the head 10. The flange 18 of the skirt 16 is notched out as at 36 at points corresponding with the spacing of the fingers 24 of the bracelet so as to receive such fingers 80 therein, for a purpose to be hereinafter described.

To assemble the parts, the skirt is pressed 85 upwardly against the head, to which the bracelet is assembled, with the fingers 24 in proper alignment with the notches 36, causing the fingers 22 and 23 of the bracelet 20 to spring inwardly until the flange 18 passes 90 the ends of the fingers 22 and 23, and abuts against the flange 15 on the head, at which time the fingers 22 and 23 are of such a length that they will just have cleared the flange 18, and will bear against the bevelled under side 19 of the flange. The fingers 22 and 23 being of unequal length, will press outwardly 95 to different extents and will always assure taking up of any play between the skirt and the head of the piston, and yet will permit the necessary movement between the head and 100

the skirt due to unequal expansion between a normally cold temperature and a temperature that may be obtained when the piston has been running under excessive compression conditions in the engine cylinder.

To maintain true concentricity between the head and skirt at all times, the extra long fingers 24 on the bracelet, and cooperating notches 36 in the flange 18 of the skirt 16 are provided. The side walls of the grooves 36 are preferably tapered so that the fingers 24 in dropping into them upon assembly of the head and skirt, will engage the sides of the respective grooves before they can reach the bottoms thereof. This insures a close fit of the fingers 24 with the sides of the grooves so as to prevent any possible movement of the head relative to the skirt in a direction perpendicular to a line connecting diametrically opposite fingers 24 in a plane parallel to the piston face. This construction permits relatively wide manufacturing tolerances in the width of the fingers 24 and grooves 36 without detracting from the proper relationship which must be maintained between the head and skirt for optimum operating results.

The portion 20 of the bracelet preferably is so constructed as to be forced home against the bottom of the groove 14 in the head 10 when the skirt is assembled to the head, and for this reason, there is little liability of possible rotation of the bracelet in the groove 14, but where more positive means for insuring against such relative movement is desired, inwardly extending projections such as 37 may be provided on the portion 20 of the bracelet, which will be forced into the softer metal of the head when the bracelet 37 is placed under compression upon assembly of the head 10 and skirt, as above described. These projections positively insure against relative movements between the bracelet and the head, and inasmuch as the fingers 24 are received within the notches 36, no relative rotational movement is permitted between the head and skirt.

Formal changes may be made in the specific embodiment of the invention described without departing from the spirit or substance of the broad invention, the scope of which is commensurate with the appended claims.

What I claim is:

1. A piston comprising a pair of members secured together in sleeved relationship by means of a collar provided with resilient fingers, and means for preventing rotation of one of said members relative to said collar comprising a radially extending projection carried by said fingers received in a depression in one of said members.

2. A piston comprising a pair of members secured together in sleeved relationship by means of a collar provided with resilient fingers, certain of said fingers engaging one of said members to lock it against rotation

relative thereto, and means for preventing said collar from rotating relative to the other of said members.

3. A piston comprising a pair of members secured together in sleeved relationship, a ring-like member encircling one of said pair of members and held against rotation thereon, and means on said ring-like member co-acting with the other of said pair of members to lock it against rotation relative to said ring-like member.

4. A piston comprising a pair of members secured together in sleeved relationship, a ring encircling one of said members and having projections received therein for preventing rotation of said ring relative to said member, and co-acting projections and depressions on the other of said members and said ring for preventing relative rotation between them.

5. A piston comprising a pair of members secured together in sleeved relationship, a ring secured against rotational movement relative to one of said members, the other of said members being provided with a notch, and a finger on said ring engaged in said notch.

6. A piston comprising a pair of members secured together in sleeved relationship, a ring secured against rotational movement relative to one of said members, the other of said members having substantially oppositely disposed notches therein, and fingers on said ring engaged in said notches.

7. A piston comprising a pair of members arranged in sleeved relationship with respect to each other, one of said members being provided with an inwardly projecting circumferential flange, a series of connected spring fingers carried by the other of said members and arranged to co-act with said flange to secure said members against separation, said flange being notched, and other spring fingers engaged in said notches to prevent rotation of one of said members relative to the other thereof.

8. A piston comprising a head member and a skirt member secured together in sleeved relationship by a plurality of spring fingers, and means for preventing rotational movement of one of said members relative to the other thereof comprising a finger of abnormal length received in a notch in one of said members.

9. A piston comprising a pair of members secured together in sleeved relationship by means of a collar provided with resilient fingers, and means for preventing rotation of one of said members relative to said collar comprising an abnormally long finger on said collar and a cooperating notch in one of said members.

10. In combination, a piston comprising a head and a skirt arranged in sleeved relationship, a circumferential groove in said head, a split ring received in said groove, inwardly
